UNITED STATES PATENT OFFICE.

OSCAR R. GUSTAFSON, OF CHICAGO, ILLINOIS, ASSIGNOR OF ONE-HALF TO GEORGE S. SCOTT, OF CHICAGO, ILLINOIS.

BELT GUARD.

Application filed February 20, 1922. Serial No. 538,101.

To all whom it may concern:

Be it known that I, OSCAR R. GUSTAFSON, a citizen of the United States, residing at Chicago, Cook County, Illinois, have invented certain new and useful Improvements in Belt Guards, of which the following is a specification.

The present improvements relate to guards for protecting the workman from injury due to his proximity to a rapidly-moving belt. Their chief objects are to provide a simple, strong, durable and effective guard which may readily be applied in its protecting position, and, in its preferred and most advantageous embodiment, without the labor and expense of boring or otherwise mutilating and also weakening the bar-like element to which it is secured; to provide a guard which may readily be adjusted 20 for use according to the requirements of the particular installation; and one which is peculiarly adapted for use in connection with a belt carried by a pulley on a swinging arm which is longitudinally adjacent to 25 the path of travel of the belt. Other objects and advantages will appear hereinafter.

In the accompanying drawings, which form a part of this specification, Figure 1 is a fragmentary perspective of a swinging saw device having a preferred embodiment of the present improvements applied thereto; Fig. 2 is an enlarged top view of one of the bracket members, with the guard proper in 35 section; Fig. 3 is an enlarged perspective of one of the clamp devices; Fig. 4 is a perspective of the clamping block; and Figs. 5, 6 and 7 are views showing how the same clamping block is adapted for use upon 40 arms or supports of different cross-sectional shapes.

The swinging saw device may be considered as of a well-known construction. It includes a swinging arm 10 mounted to rock 45 on the axis of the pulley 11 on the shaft 12, and a belt 14 on the pulleys 11 and 15, the latter being mounted at the lower end of the arm 10 for driving the saw 16. The operator moves the swinging arm and saw 50 back and forth by means of a handle as 17 shown as being secured upon the arm 10.

My improved guard device includes a clamp block 19 having a substantially-V-shaped opening 20 in one side adapted to 55 engage and grip the arm 10, or the arms 21,

22 and 23 (Figs. 5, 6 and 7) as well as arms or supports of still other cross-sectional forms. The outer surfaces of the block 19 is preferably formed with a recessed transverse seat at 24 defined by marginal ribs 60 or projections 25 whereby a bracket member, as the flat bar 26 (Fig. 1) may be held firmly upon the block by a single bolt. The block 19 is provided with a transverse bolt recess 27 at each end whereby two bolt members as 28 may be applied to or removed from the block without removing the nuts 30. The block 19 is preferably a casting and, for the sake of lightness as well as to accommodate the bolts 28 and the hooks 70 upon them, it is preferably hollowed out, as well shown in Figs. 3 and 4, whereby the part of the block which contacts the arm as 10 is substantially in the form of two spreading flanges each having a substantially-V-shaped opening 20. Preferably two such blocks are used, as shown in Fig. 1.

Each of the clamping bolts 28 has a hook 32 upon which is held readily removably an adjustable flexible member shown as a chain 80 33. The bracket bar 26 is slotted at 29 for the bolt 28, and when the parts are assembled as in Fig. 1 the bar 26 is held securely and for lateral adjustment by one of the bolts 28, and the block 19 is held firmly upon the arm as 10 by both bolts 28 and the chain 33 passing around the arm, as well shown in Fig. 5. The block 19 may thus be readily clamped upon the arm without dismantling the saw device in any way, without boring, 90 and without any other mutilation of the arm. The slot-like recesses 27 in the block enable the bolts 28 to be positioned so as to accommodate arms, as 10, of various widths and to bring the flexible member 95 close to the sides of the arm for better holding effect. The chain 33 is materially long whereby it may be hooked upon the bolts 28 at such links as will make it of the desired effective length for arms, as 10, of 100 various thicknesses.

A guard proper 35 shown as a flat piece of sheet material, such as thin sheet metal, is held in overlying position with respect to the belt 14 by connections intermediate 105 the block and the guard proper. These connections include the plate or bar 26 already mentioned. Another bracket part is the bar 36 having a longitudinal slot 37 for the bolt 38 adapted to hold the guard 35 upon 110

the bar 36; and the bolt 39 is also in this slot 37. Another bracket part is the plate or bar 40 having a slot 41 for the bolt 39.

The bracket part 40 has its end at 42 formed at right angles to the general direction of this part and this end 42 has a hole for the bolt 43 which bolt is accommodated in a slot 44 in the bracket part 26.

From this construction it is clear that the 10 guard proper 35 may be adjusted so as to overlie belts traveling on pulleys of different diameters by means of the bolt 43 in the slot 44, and that the guard 35 may be adjustably positioned in a direction at right 15 angles to the one just mentioned by means of the bolts 38 and 39. It is also clear that another guard as 35 may be positioned on the opposite side of the arm 10 if desired, or that a guard as 35 may be positioned so as 20 to overlie either section of the belt as the particular situation may suggest.

The importance of a guard of this character is that without such protection breakage 25 of the belt is likely to result in severe injury to the workman standing immediately in front of the belt when the saw is being used. The guard also protects his saw-swinging hand and arm, and it also avoids contact with the belt by lumber pieces being handled.

30 Reference should be had to the appended claims to determine the scope of the improvements herein set forth.

I claim:

1. The combination of a pair of pulleys 35 spaced apart, a belt operatively on said pulleys, one of said pulleys being carried by an arm mounted to rock on the axis of the other pulley, clamping means on said swinging arm, a guard proper overlying the belt, and 40 means between the guard proper and the clamping means for holding the guard proper in its belt-overlying position.

2. The combination of a pair of pulleys 45 spaced apart, a belt operatively on said pulleys, one of said pulleys being carried by an arm mounted to rock on the axis of the

other pulley, clamping means on said swinging arm, a guard proper overlying the belt, and adjustable means between the guard proper and the clamping means for holding 50 the guard proper in its belt-overlying position.

3. A belt guard of the character described comprising in combination a pair of clamping members each of which has a jaw adapted 55 to engage a bar adjacent to a belt, means cooperating with said clamping members respectively for holding the clamping members rigidly upon such bar, a guard proper adapted to overlie the belt adjacent to such bar, 60 and connection means between the guard proper and said clamping members respectively for holding the guard proper in its belt-overlying position.

4. A belt guard of the character described 65 comprising in combination clamping means including a member having a pair of laterally-disposed openings for a pair of bolt members, a pair of bolt members in said openings, flexible clamping members carried 70 by the bolt members, the arrangement being such that said member may be held tightly upon a bar of the character described, a bracket member held adjustably by said clamp members, and a belt guard proper 75 held adjustably by said bracket member.

5. A guard of the character described comprising clamping means including a block-like member having a substantially wedge-shaped recess in one side adapted to receive 80 a rod-like member, bolt members carried laterally by said block-like member, a flexible member carried by the bolt members, the arrangement being such that such rod-like member may be positioned between the block 85 member and the flexible member, nuts on the bolt members arranged to draw the block member toward the flexible member, a bracket device held adjustably on the clamping means, and a guard proper carried by 90 the bracket device.

OSCAR R. GUSTAFSON.
